DESIGN FOR A MILK BOTTLE

Leon J. Weatherwax, Toledo, Wash., assignor of
fifty per cent to Robert B. Menefee and fifty per
cent to Stella Menefee, both of Toledo, Wash.

Application May 3, 1940, Serial No. 92,120

Term of patent 14 years

To all whom it may concern:

Be it known that I, Leon J. Weatherwax, a citizen of the United States, residing at Toledo, in the county of Lewis and State of Washington, have invented a new, original, and ornamental Design for Milk Bottles, of which the following is a specification, reference being had to the accompanying drawing, forming part thereof.

Fig. 1 is a side elevational view of the milk bottle showing my new design:

Fig. 2 is a rear view thereof; and
Fig. 3 is a view of the side opposite to that shown in Fig. 2 on a somewhat reduced scale.

I claim:

The ornamental design for a milk bottle, as shown.

L. J. WEATHERWAX.
